(57) **CLAIM**

The ornamental design for a stove as shown and described.

DESCRIPTION

FIG. 1 is a perspective view of a stove showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the stove with parts shown separated;

FIG. 10 is a state of use perspective view of the stove with a lid applied; and,

FIG. 11 is an enlarged view of area 11 shown in FIG. 1. The broken lines depict portions of the stove that form no part of the claimed design.

1 Claim, 11 Drawing Sheets
